UNITED STATES PATENT OFFICE

2,511,822

LOOM HARNESS

John Jacob Kaufmann, Elkins Park, Pa., assignor
to Steel Heddle Manufacturing Company, Philadelphia, Pa., a corporation of Pennsylvania

Application August 21, 1945, Serial No. 611,773

8 Claims. (Cl. 139—92)

1

The invention relates to loom harness, and it relates more particularly to that type of harness which is used in installations where the warp ends are entered or inserted through the heddle eyes by means of the automatic drawing-in machines which are now in more or less common use in textile mills.

As is well known, in those installations in which the warp is entered or drawn in by means of automatic warp drawing-in machines, it is essential that the heddles have entire freedom of movement on the heddle rods from one end of the frame to the other. Hence, in such installations, it is not possible to use heddle frames having means for supporting the heddle rods intermediate their ends of the type commonly referred to in the industry as "hooks," for the reason that it is not possible for the heddles to pass said "hooks," as is required in the automatic drawing-in operation, without first disengaging the heddle rods therefrom, and such action is impractical when the entering is done by means of the automatic machines.

The principal object of the present invention is to provide a novel and relatively inexpensive form of heddle frame, in which the means for supporting the heddle rods intermediate their ends is so constructed and arranged as to offer no obstruction to the free passage of the heddles along the rods and past the supporting devices.

A further object of the invention is to provide, in the heddle frames of loom harness, novel means for supporting the heddle rods intermediate their ends, so that deformations of the wooden rails, at the top and bottom of the heddle frames, due to working stresses or to climatic conditions, will not be transmitted to the heddle supporting rods and thereby deflect the same out of parallelism and cause the heddles to bind on said rods.

A further object of the invention is to provide, in heddle frames of the type in which an auxiliary bar forms part of the means for supporting the heddle rods intermediate their ends, novel means for securing said auxiliary bars in the heddle frames.

The nature and characteristic features of the invention will be more readily understood from the following description, taken in connection with the accompanying drawings forming part hereof, in which;

Figure 1 is a front elevation, partly broken away, of a loom harness frame embodying the main features of the present invention, the same being shown provided with heddles which are

2

adapted for use in installations in which an automatic warp drawing-in machine is used for entering the warp in the eyes of the heddles;

Fig. 2 is an enlarged vertical section thereof, taken approximately on the line 2—2 of Fig. 1;

Fig. 3 is a fragmentary perspective view illustrating parts of the means for supporting the heddle rods intermediate the ends thereof, and illustrating the end portions of some of the preferred form of heddles employed in the frame;

Fig. 4 is a perspective view of the portion of the structure shown in Fig. 3, but looking from the other side thereof; and

Fig. 5 is a fragmentary perspective view of one end of an auxiliary bar forming part of the structure for supporting the heddle rods intermediate the ends thereof.

It should, of course, be understood that the description and drawings herein are illustrative merely, and that various changes and modifications may be made in the structure disclosed without departing from the spirit of the invention.

Referring to the drawings, the heddle frame proper may be of any preferred construction. For example, as shown, the same may comprise top and bottom rails 10, connected at their ends by end struts 11. The heddle supporting rods 12 are preferably made of strips of flat bar metal, extending from end to end of the frame, and each having its end portions extending through slots in the end struts 11 of the frame in the usual and customary manner.

Each of the projecting end portions of each heddle rod 12 may also be provided with the usual aperture 13, engaged by the hooked end 14 of a spring retaining member 15 mounted in one of the end struts 11 of the frame.

It will, of course, be readily understood that various other forms of retaining means, at the ends of the heddle rods 12 may be used if desired, although it has been found that the spring members 15 of the character shown, are quite satisfactory for the purpose.

Each of the top and bottom rails 10 is provided, along its inner edge portion, with a groove or recess 20 in which a bar 24 is mounted. The bar 21 is preferably made of flat bar metal slightly heavier than the heddle supporting rods 12. The bar 21 has, at each end, a tapered slot or notch 22 (see Fig. 5), which engages, in each instance, the inner end of a member 23 which may be an extension from one of the members of one of the end struts 11. However, the members 23 may, if desired, be separate members se-

cured at the inner edge portion of each rail 18 at the ends thereof.

At each of the locations where it is desired to support a heddle rod 12 intermediate its ends, the bar member 21 is provided with a slot 24, one portion 25 of which is larger in width than the other portion 26 thereof, for a purpose to be presently explained.

At a location on each heddle rod 12 complementary to that of the slot 24 of the bar 21, there is provided a bracket member 27 which extends horizontally outward from one side face of the heddle rod, and thence extends in a plane parallel to that of the heddle rod. The outer end of the member 27 has a pair of rivets 28 extending therethrough which serve to support a spacer block 29 and a head plate 30. The block 29 is of a width corresponding to the narrow portion 25 of the slot 24, whereas the head plate 30 is of a greater width but is adapted to pass through the wider portion 26 of the slot 24 in the bar 21.

By the foregoing arrangement there is provided means for supporting each heddle bar intermediate its ends which is so constructed and arranged that, by sliding the heddle rod lengthwise in the frame the head plates 30 may be brought into register with the wider portions 26 of the slots 24 in the bar 21, thereby to permit the heddle rod to be detached from the bar 21 by passing the head plate 30 therethrough.

When the heddle rod is to be mounted in the frame, one end of the heddle rod 12 is first inserted in its slot in one of the end struts 11, and the heddle rod 12 is then brought to a position with the head plates 30 in register with the wider parts 26 of the slots 24 in the bar 21, after which the head plates 30 are passed through the wider portions 26 of the slot 24. The other end of the heddle rod 12 is then inserted in its slot in the end strut 11 of the heddle frame, after which the entire structure of the heddle rod, with the parts carried thereby, is then slid lengthwise, the ends of the heddle rod being finally mounted in the slots in the end strut 11. When the heddle rod is slid lengthwise the proper distance, the apertures 13 in the heddle rods 12 are engaged by the hooked ends 14 of the spring retaining members 15.

The heddles 31 may be substantially similar to those shown in Figs. 2 and 3 of my previous Letters Patent No. 2,047,511, being made from thin flat strips of metal of a width corresponding to the widest portion of the heddle. However, the metal of each heddle 31 is preferably left the full width of the strip from end to end and the central portion of each heddle 31 is provided with the usual punched and formed warp eye 32, the shanks of which may, if desired, be formed in bowed conformation out of the plane of the heddle proper to facilitate the entrance of the needle of the drawing-in machine, as well also to afford greater freedom in the passage of the warp as the shedding takes place during the weaving operation.

It should, of course, be understood that the number of the devices required for supporting the heddle rods intermediate their ends will depend in a large measure upon the width of the harness frame. A plurality of such supports will usually be provided, both at the top and bottom, although but one is shown in the drawing at the top and another at the bottom.

It will be noted that, by the foregoing arrangement, there is provided a novel form of heddle frame which is so constructed and arranged that

the heddle rods may be quickly and easily removed and replaced in the frame, and further that the arrangement is such that the parallelism of the heddle rods will be maintained at all times, whereby binding of the heddles on the heddle rods is avoided, and this notwithstanding the top and bottom rails may become deformed and bent due to the strains imposed in operation, as well as due to climatic changes which occur from time to time.

It will also be seen that in a heddle frame constructed as aforesaid, each auxiliary bar 21 and its associated heddle rod 12 will, when the parts are brought to their operative positions, constitute in effect a composite beam with effective resistance to the bending stresses to which the heddle rod is subjected each time the shed is formed in the weaving operation.

I claim:

20. 1. In a loom harness including a heddle frame having top and bottom rails, heddle supporting rods comprising thin flat metallic strips mounted in said frame, and heddles mounted on said rods and adapted to be freely movable on said rods without obstruction, the means for supporting said rods intermediate the ends thereof comprising an auxiliary bar adjacent each of said heddle rods and having a portion extending inwardly from the inner edge of the rail, and the provision, at each location, of a bracket member carried by and fixedly secured to the rod and extending from one side face thereof and said bracket member having said inwardly extending part detachably engaging a portion of said auxiliary bar, said auxiliary bar extending substantially the full length of the frame and being secured thereto only at points adjacent the ends thereof.
25. 2. In a loom harness including a heddle frame having top and bottom rails, heddle supporting rods comprising thin flat metallic strips mounted in said frame, and heddles mounted on said rods and adapted to be freely movable on said rods without obstruction, the means for supporting said rods intermediate the ends thereof comprising an auxiliary bar adjacent each of said heddle rods and having a portion extending inwardly from the inner edge of the rail, and the provision, at each location, of a longitudinal slot in said inwardly extending portion of said auxiliary bar, a bracket member carried by and fixedly secured to the rod and extending from one side face thereof, and a member carried by said bracket member detachably engaging the slot in said auxiliary bar, said auxiliary bar extending substantially the full length of the frame and being secured thereto only at points adjacent the ends thereof.
30. 3. In a loom harness including a heddle frame having top and bottom rails, heddle supporting rods comprising thin flat metallic strips mounted in said frame, and heddles mounted on said rods and adapted to be freely movable on said rods without obstruction, the means for supporting said rods intermediate the ends thereof comprising an auxiliary bar adjacent each of said heddle rods and having a portion extending inwardly from the inner edge of the rail, and the provision, at each location, of a longitudinal slot in said inwardly extending portion of said auxiliary bar, a bracket member carried by and fixedly secured to the rod and extending from one side face thereof, and a member carried by said bracket member detachably engaging the slot in said auxiliary bar, said auxiliary bar extending substantially the full length of the frame and being secured thereto only at points adjacent the ends thereof.
35. 4. In a loom harness including a heddle frame having top and bottom rails, heddle supporting rods comprising thin flat metallic strips mounted in said frame, and heddles mounted on said rods and adapted to be freely movable on said rods without obstruction, the means for supporting said rods intermediate the ends thereof comprising an auxiliary bar adjacent each of said heddle rods and having a portion extending inwardly from the inner edge of the rail, and the provision, at each location, of a longitudinal slot in said inwardly extending portion of said auxiliary bar, a bracket member carried by and fixedly secured to the rod and extending from one side face thereof, and a member carried by said bracket member detachably engaging the slot in said auxiliary bar, said auxiliary bar extending substantially the full length of the frame and being secured thereto only at points adjacent the ends thereof.
40. 5. In a loom harness including a heddle frame having top and bottom rails, heddle supporting rods comprising thin flat metallic strips mounted in said frame, and heddles mounted on said rods and adapted to be freely movable on said rods without obstruction, the means for supporting said rods intermediate the ends thereof comprising an auxiliary bar adjacent each of said heddle rods and having a portion extending inwardly from the inner edge of the rail, and the provision, at each location, of a longitudinal slot in said inwardly extending portion of said auxiliary bar, a bracket member carried by and fixedly secured to the rod and extending from one side face thereof, and a member carried by said bracket member detachably engaging the slot in said auxiliary bar, said auxiliary bar extending substantially the full length of the frame and being secured thereto only at points adjacent the ends thereof.
45. 6. In a loom harness including a heddle frame having top and bottom rails, heddle supporting rods comprising thin flat metallic strips mounted in said frame, and heddles mounted on said rods and adapted to be freely movable on said rods without obstruction, the means for supporting said rods intermediate the ends thereof comprising an auxiliary bar adjacent each of said heddle rods and having a portion extending inwardly from the inner edge of the rail, and the provision, at each location, of a longitudinal slot in said inwardly extending portion of said auxiliary bar, a bracket member carried by and fixedly secured to the rod and extending from one side face thereof, and a member carried by said bracket member detachably engaging the slot in said auxiliary bar, said auxiliary bar extending substantially the full length of the frame and being secured thereto only at points adjacent the ends thereof.
50. 7. In a loom harness including a heddle frame having top and bottom rails, heddle supporting rods comprising thin flat metallic strips mounted in said frame, and heddles mounted on said rods and adapted to be freely movable on said rods without obstruction, the means for supporting said rods intermediate the ends thereof comprising an auxiliary bar adjacent each of said heddle rods and having a portion extending inwardly from the inner edge of the rail, and the provision, at each location, of a longitudinal slot in said inwardly extending portion of said auxiliary bar, a bracket member carried by and fixedly secured to the rod and extending from one side face thereof, and a member carried by said bracket member detachably engaging the slot in said auxiliary bar, said auxiliary bar extending substantially the full length of the frame and being secured thereto only at points adjacent the ends thereof.
55. 8. In a loom harness including a heddle frame having top and bottom rails, heddle supporting rods comprising thin flat metallic strips mounted in said frame, and heddles mounted on said rods and adapted to be freely movable on said rods without obstruction, the means for supporting said rods intermediate the ends thereof comprising an auxiliary bar adjacent each of said heddle rods and having a portion extending inwardly from the inner edge of the rail, and the provision, at each location, of a longitudinal slot in said inwardly extending portion of said auxiliary bar, a bracket member carried by and fixedly secured to the rod and extending from one side face thereof, and a member carried by said bracket member detachably engaging the slot in said auxiliary bar, said auxiliary bar extending substantially the full length of the frame and being secured thereto only at points adjacent the ends thereof.
60. 9. In a loom harness including a heddle frame having top and bottom rails, heddle supporting rods comprising thin flat metallic strips mounted in said frame, and heddles mounted on said rods and adapted to be freely movable on said rods without obstruction, the means for supporting said rods intermediate the ends thereof comprising an auxiliary bar adjacent each of said heddle rods and having a portion extending inwardly from the inner edge of the rail, and the provision, at each location, of a longitudinal slot in said inwardly extending portion of said auxiliary bar, a bracket member carried by and fixedly secured to the rod and extending from one side face thereof, and a member carried by said bracket member detachably engaging the slot in said auxiliary bar, said auxiliary bar extending substantially the full length of the frame and being secured thereto only at points adjacent the ends thereof.
65. 10. In a loom harness including a heddle frame having top and bottom rails, heddle supporting rods comprising thin flat metallic strips mounted in said frame, and heddles mounted on said rods and adapted to be freely movable on said rods without obstruction, the means for supporting said rods intermediate the ends thereof comprising an auxiliary bar adjacent each of said heddle rods and having a portion extending inwardly from the inner edge of the rail, and the provision, at each location, of a longitudinal slot in said inwardly extending portion of said auxiliary bar, a bracket member carried by and fixedly secured to the rod and extending from one side face thereof, and a member carried by said bracket member detachably engaging the slot in said auxiliary bar, said auxiliary bar extending substantially the full length of the frame and being secured thereto only at points adjacent the ends thereof.
70. 11. In a loom harness including a heddle frame having top and bottom rails, heddle supporting rods comprising thin flat metallic strips mounted in said frame, and heddles mounted on said rods and adapted to be freely movable on said rods without obstruction, the means for supporting said rods intermediate the ends thereof comprising an auxiliary bar adjacent each of said heddle rods and having a portion extending inwardly from the inner edge of the rail, and the provision, at each location, of a longitudinal slot in said inwardly extending portion of said auxiliary bar, a bracket member carried by and fixedly secured to the rod and extending from one side face thereof, and a member carried by said bracket member detachably engaging the slot in said auxiliary bar, said auxiliary bar extending substantially the full length of the frame and being secured thereto only at points adjacent the ends thereof.

ends thereof and each of the heddles being made of a strip of material having a slot in each end portion for mounting the heddle on the supporting rods, the metal on one side of each of said slots, having an opening to permit the heddle to pass the bracket members.

4. In a loom harness including a heddle frame having top and bottom rails, heddle supporting rods comprising thin flat metallic strips mounted in said frame, and heddles mounted on said rods and adapted to be freely movable on said rods without obstruction, the means for supporting said rods intermediate the ends thereof comprising an auxiliary bar adjacent each of said heddle rods and having a portion extending inwardly from the inner edge of the rail, and the provision, at each location, of a longitudinal slot in said inwardly extending portion of said auxiliary bar, a bracket member carried by and fixedly secured to the heddle rod and extending from one side face thereof, and a member carried by said bracket member detachably engaging the slot in said auxiliary bar, said auxiliary bars extending substantially the full length of the frame and also being positioned in recesses in the top and bottom rails and being secured to the top and bottom rails at their end portions only.

5. In a loom harness including a heddle frame having top and bottom rails, heddle supporting rods comprising thin flat metallic strips mounted in said frame, and heddles mounted on said rods and adapted to be freely movable on said rods without obstruction, the means for supporting said rods intermediate the ends thereof comprising an auxiliary bar adjacent each of said heddle rods and having a portion extending inwardly from the inner edge of the rail, and the provision, at each location, of a longitudinal slot in said inwardly extending portion of said auxiliary bar, a bracket member carried by and fixedly secured to the rod and extending from one side face thereof, and a member carried by said bracket member detachably engaging the slot in said auxiliary bar, said auxiliary bars also having portions positioned in recesses in the top and bottom rails and extending substantially the full length of the frame and also being secured to the top and bottom rails at their end portions only, and each of the heddles being made of a strip of metal having a slot in each end portion for mounting the heddle on the supporting rods, the metal on one side of each of said slots having an opening to permit the heddle to pass the bracket members.

6. In a loom harness including a heddle frame having top and bottom rails, heddle supporting rods comprising thin flat metallic strips mounted in said frame, and heddles mounted on said rods, the means for supporting said rods intermediate the ends thereof comprising an auxiliary bar ad-

jacent each of said heddle rods, and the provision, at each location, of means for detachably connecting said heddle rods to said auxiliary bars, said auxiliary bars being positioned in recesses in the top and bottom rails and having tapered notches at their end portions and members fixedly secured to the end portions of the rails and engaging said notches.

7. In a loom harness including a heddle frame having top and bottom rails, heddle supporting rods comprising thin flat metallic strips mounted in said frame, and heddles mounted on said rods, the means for supporting said rods intermediate the ends thereof comprising an auxiliary bar adjacent each of said heddle rods and having a portion extending inwardly from the inner edge of the rail, and the provision, at each location, of means for detachably connecting said heddle rods to said auxiliary bars comprising a longitudinal slot in the inwardly extending portion of said auxiliary bar, a bracket member carried by and fixedly secured to the heddle rod, and a part carried by said bracket member engaging said slot, said auxiliary bar extending substantially the full length of the frame and being secured thereto only at points adjacent the ends thereof.

8. In a loom harness including a heddle frame having top and bottom rails, heddle supporting rods comprising thin flat metallic strips mounted in said frame, and heddles mounted on said rods, the means for supporting said rods intermediate the ends thereof comprising an auxiliary bar adjacent each of said heddle rods and having a portion extending inwardly from the inner edge of the rail, and the provision, at each location, of means fixedly secured to the heddle rod for detachably connecting said heddle rod to the auxiliary bar, said auxiliary bars extending substantially the full length of the frame and being secured in the frame at their ends only and also having portions positioned in recesses in the top and bottom rails.
